(71) Applicant: **Meta Platforms, Inc.**
(72) Inventor: **Debashish Paul**, Sunnyvale, CA (US)
(73) Assignee: **Meta Platforms, Inc.**, Menlo Park, CA (US)

(**) Term: **15 Years**(21) Appl. No.: **29/755,346**(22) Filed: **Oct. 20, 2020****Related U.S. Application Data**

(63) Continuation of application No. 29/665,928, filed on Oct. 8, 2018, now Pat. No. Des. 904,425.
(51) LOC (14) Cl. 14-04
(52) U.S. Cl.
USPC D14/485
(58) Field of Classification Search
USPC D14/485-495
CPC H04M 1/724-72484

See application file for complete search history.

Primary Examiner — Rachel A. Voorhies(74) *Attorney, Agent, or Firm* — Greenberg Traurig, LLP(57) **CLAIM**

The ornamental design for a display screen with a graphical user interface, as shown and described.

DESCRIPTION

The sole FIGURE is a front view of a display screen with a graphical user interface showing the claimed design. The broken lines shown in the sole FIGURE show portions of the environment and form no part of the claimed design. The lines depicting the device in which the display screen is displayed, the x icon, the back icon, the upper circle and elements within the upper circle, the central rectangle and elements within the central rectangle, the lower sliding element and lock and silhouettes to each side of the sliding element, and all of the illustrated text are broken lines and form no part of the claimed design.
